FLASH PLUG

Josephat Fredette, St. Jean Baptiste,
Manitoba, CanadaApplication October 7, 1932, Serial No. 636,673
In Canada August 29, 1932

1 Claim. (Cl. 123—169)

The invention relates to improvements in flash plugs and an object of the invention is to provide an improved plug of simple design which can be manufactured at comparatively small cost and having the parts all designed so that they can be easily and quickly assembled in the well known manner.

A further object of the invention is to provide a plug having a stationary exposed electrode and a slotted receptacle enclosing the same and containing a spherical ball freely movable in the receptacle and operating to maintain the parts free of deposit and accordingly clean.

A still further object is to construct the receptacle so that the compressed charge can pass freely and directly into the receptacle and be effectively distributed over the entire cross sectional area thereof and further such that the ball when riding the bottom of the receptacle or engaged with the sides thereof, will be at a constant distance from the stationary electrode, thereby maintaining a constant gap in all positions of the ball.

A still further object of the invention is to construct the bottom of the receptacle on which the ball rides so that it offers a minimum resistance to the shifting of the ball in any direction, such arrangement insuring that the parts will be maintained clean or free from deposit due to the continuous rolling movement of the ball.

A further object is to provide the receptacle with a flat bottom on which the ball rides and the electrode with an exposed end parallel thereto, such resulting in the maintaining of the ball at a constant distance from the electrode as it shifts within the receptacle, it being understood that the sides of the receptacle limit the side movement of the ball in respect to the electrode.

A further object of the invention is to provide a plug which will give in all positions of the ball within the receptacle a relatively large evenly distributed flash when the plug is in use, the flash actually when under observation, having the appearance of an annular illuminated ring around the ball.

With the above more important objects in view, the invention consists essentially in the arrangement and construction of parts hereinafter more particularly described, reference being had to the accompanying drawing, in which:—

Fig. 1 is a side view of the plug.

Fig. 2 is an enlarged detailed vertical sectional view at 2—2 Figure 1.

Fig. 3 is a vertical cross sectional view at 3—3

Figure 2 and showing the ball in a changed position.

Fig. 4 is a horizontal cross sectional view at 3—3 Figure 2 and showing the ball in a changed position.

In the drawing like characters of reference indicate corresponding parts in the several figures.

The central stem 1 of the plug has the upper end thereof screw threaded to receive the customary terminal nut 2 directly under which is located a metal washer 3 which rests on the upper end of the porcelain insulator 4. It will be observed that the lower end of the stem terminates in an enlarged head 5 which is seated or countersunk in the lower end of the insulator and which forms an exposed central electrode. The porcelain insulator is of the usual shape and presents a bulbous portion 6.

A metallic shell 7 is supplied and the shell has the lower end externally screw threaded as indicated at 8 and the upper end internally screw threaded as indicated at 9 and it is supplied with an internal tapering seat 10 adapted to support the bulbous portion of the porcelain. A gas proof packing 11 is interposed between the seat and the porcelain as shown and the upper end of the shell receives a screw threaded bushing 12 and between the bushing and the bulbous portion of the insulator, a second gas proof packing 13 is inserted.

The above parts with the exception of the specific construction of the lower end of the stem, are well known so a detailed description of the same is not herein given, it being sufficient for the purpose of the present disclosure to understand that the inserted porcelain is held firmly in place between the seat of the shell and the bushing when the bushing is screwed down, the packings insuring at such time of gas tight joints.

The lower end of the shell is formed to provide an integral ball receptacle 14 having a plurality of cross slots 15 therein. Actually the receptacle is initially in the form of a cylinder having a closed bottom and the cylinder and bottom are subsequently cross cut vertically such as by a saw to provide the slots which are preferably equi-spaced and pass across the bottom of the receptacle and up the side walls thereof.

Within the receptacle, I locate a metallic ball 16 forming a movable electrode, such ball having a predetermined selected diameter.

It will be particularly noted that the inner face of the receptacle bottom is horizontal or flat and that the exposed face of the electrode 5 is parallel thereto with the result that the gap between

the ball and the electrode 5 is maintained constant irrespective of the position of the ball when riding the receptacle. Attention is here directed to Figure 3 where the ball is at the side of the receptacle and in this figure, it will be observed that the side wall of the receptacle has stopped the ball with its uppermost point directly underlying the peripheral edge of the electrode 5 so that in all side positions of the ball, the gap is the same as in the central or any intermediate position.

The relative arrangement of the electrode 5, the ball and the receptacle, not only provide a plug which will maintain a constant spark gap but the flat inner face of the receptacle has the further very desirable advantage that it offers a minimum resistance to the shifting of the ball when the plug is in use with the result that the ball is practically continuously in movement and accordingly very effectively maintains the associated parts free of deposit or clean. It will be readily seen that if the plug is tilted in any direction from the vertical, the ball will immediately roll to the low side and in actual practice, a plug is being shifted to cause the almost continuous rolling of the ball.

It will also be observed that the shape of the receptacle is such that when the plug is in use, the compressed firing charge will be passed di-

rectly into the receptacle through the slots and distributed evenly throughout the entire cross sectional area of the interior of the receptacle.

I may say that I have made plugs as herein disclosed and have placed them under observation and I find that in all positions of the ball, there is an annular flash surrounding the ball which is quite distinct to a spark at a single point.

What I claim as my invention is:—

In a flash plug, a substantially cylindrical metallic shell having the lower end thereof closed by a flat lying bottom and forming a receptacle at the lower end of the shell and having the bottom and side walls of the receptacle cross slotted at spaced intervals, a ball normally riding the bottom of the receptacle and forming one electrode, an insulating member mounted in the shell and overlying the receptacle and a second electrode in the form of a circular stem extending centrally through the insulating member and carried by the insulating member and terminating in an enlarged circular area presenting a face exposed to the receptacle and parallel to the bottom of the receptacle, the distance between the latter face and the bottom of the receptacle being greater than the diameter of the ball whereby a gap is reserved between the top of the ball and said exposed face.

JOSEPHAT FREDETTE. 30
